SIGNALING SYSTEM

Filed Feb. 23, 1927

Inventor:
Alfred C. Finney,
by Alfred C. Finney
His Attorney.

UNITED STATES PATENT OFFICE

ALFRED C. FINNEY, OF UPPER DARBY, PENNSYLVANIA, ASSIGNOR TO GENERAL ELECTRIC COMPANY, A CORPORATION OF NEW YORK

SIGNALING SYSTEM

Application filed February 23, 1927. Serial No. 170,201.

My invention relates to signaling systems and has for its object the provision of a simple and reliable system of signaling between two remotely located stations, in which provision is made for an answer-back signal.

My invention has particular application in electric power stations and systems in the transmission of orders from a control or transmitting station to a remotely located engine room constituting a receiving station. In carrying out my invention in one form I provide an indicating device in each station which may be operated by a control device in each station. Each control device is provided with means associated therewith so that when it is operated to give a signal the other control device is rendered inoperative. In the operation of the system, when the transmitting operator has given a signal, the receiving operator moves his control device as if to repeat the signal which disconnects the transmitting control device whereupon the indicators return to zero. The transmitting operator upon observing this returns his control device to starting position which reconnects the receiving control device, and the receiving operator then repeats the signal to show that it has been correctly received. I also provide a visible or audible alarm device whereby one operator may attract the attention of the other.

For a more complete understanding of my invention reference should be had to the accompanying drawing the single figure of which is a diagrammatic representation of a signaling system embodying my invention.

Referring to the drawing, my invention in one form comprises two electrical indicating devices 10 and 11 placed in the sending and receiving stations respectively. The indicating devices are suitable electrical instruments, and in the arrangement shown are voltage responsive instruments, such as volt meters. In order to control the indicators two potential rheostats 12 and 13 are provided at the sending and receiving stations respectively, these rheostats being each electrically connected by conductors 14 and 15 across a suitable electrical source of supply 16. The rheostats 12 and 13 are each provided with a num-

ber of taps leading to contacts with which cooperate arms 17 and 18 respectively. Associated with the contact arm 17 is a relay switch comprising a bridging contact 19 which may be moved between two pairs of stationary contacts 20 and 21. A spring 22 is provided whereby the bridging contact 19 is biased to engage the contacts 20, while an arm 23 is provided in the path of the contact arm 17 whereby when the contact arm is moved to off position as shown in the drawing, the bridging contact is moved against the force of the spring 22 to engage the contacts 21 and establish a circuit from one to the other. A similar switching device 24 is provided in connection with the contact arm 18, the construction and operation of which will be understood from the previous description of the device associated with the contact arm 17.

Each indicator is connected through a conductor 25 directly to one side of the supply source 16. The other terminal of the indicator 10 is connected through a conductor 25^a, the pair of contacts 21, and the conductor 26, to the switch arm 18. In a similar manner the other terminal of the indicator 11 is connected through a conductor 27, the lower pair of contacts of the switch 24, and the conductor 28, to the switch arm 17. These two terminals of the indicators are also connected directly together by means of a conductor 29. With these connections it will be observed that when either contact arm is in off-position, as shown in the drawing, a control circuit for the indicators is established for the other contact arm, and also it will be observed that when either contact arm is moved from off-position to operate the indicators the control circuit for the other contact arm is thereby broken. The contact arm 17 is biased toward the off-position, as shown in the drawing, by means of a spring 17^a so that when the contact arm is released by the operator it will be immediately returned by the spring to the off position.

Suitable alarm devices, shown as bells, 30 and 31 are provided at the sending and receiving stations respectively, whereby the attention of the operators may be directed to the indicators. The bell 30 has one terminal

connected to one side of the supply circuit 16 and its other terminal connected through a conductor 32 and the upper pair of contacts of the switch 24 to the other side of the supply source. Bell 31 has one terminal connected to one side of the supply source through a conductor 33 and its other terminal connected through a conductor 34 and the pair of contacts 20 to the other side of the supply source. A lamp 35 connected in parallel with the bell 31 may be also provided in the receiving station. With these connections for the alarm devices, it will be observed that when both contact arms are in off-position, as shown in the drawing, the alarm devices are not operated. When the contact arm 17, however, is moved to operate the indicators a circuit for the alarm 31 in the receiving station is closed by the bridging contact 19 engaging the pair of contacts 20, and in a similar manner when the contact arm 18 is moved from off-position a circuit for the bell 30 is closed by the bridging device of the switch 24 through the upper pair of contacts.

In the operation of the system the operator at the transmitting station moves the arm 17 to produce the desired indication on the indicator 10, the same indication being produced by the indicator 11. This, at the same time, causes the alarm 31 to operate and also lights the lamp 35 to attract the attention of the operator in the receiving station who upon observing the signal moves his contact arm 18 from off-position as if to repeat the signal. This causes the switch 24 to open the circuit for the indicators whereby the indicators immediately return to zero. At the same time the alarm 30 is sounded in the transmitting station to indicate to the sending operator that the receiving operator is repeating the signal. The operator in the transmitting station thereupon returns his contact arm 17 to off-position or releases it to allow the spring 17^a to return it to off-position. This closes a control circuit for the contact arm 18 through the contacts 21 whereupon the receiving operator moves the contact arm 18 to repeat the signal he has received which is shown on the two devices 10 and 11 whereby the sending operator can be assured that it has been received correctly. The receiving operator then returns his contact arm 18 back to the off-position, as shown in the drawing, so that the system is then ready for the transmission of another signal by the transmitting operator, when desired.

While I have described my invention as embodied in concrete form and as operating in a specific manner in accordance with the provisions of the patent statutes, it should be understood that I do not limit my invention thereto since various modifications thereof will suggest themselves to those skilled in the art without departing from the spirit of

my invention the scope of which is set forth in the annexed claims.

What I claim as new and desire to secure by Letters Patent of the United States, is:—

1. A signaling system comprising sending and receiving stations, electrical indicating devices in said stations, a control device in each of said stations for said indicators, each control device being provided with an off position and with a plurality of controlling positions, electrical connections between said control devices and said indicators whereby each of said control devices actuates both of said indicators when either is moved from its off position and each control device being provided with means associated with said electrical connections to effect a graduated control of said indicators when said control device is moved to its controlling positions, and means operated by each control device for disconnecting the other control device. 70 75 80 85

2. A signaling system comprising sending and receiving stations, an indicating device in each of said stations, a transmitting control device in said sending station for said indicators, a receiving control device in said receiving station for said indicators, each control device being provided with an off position and with a plurality of controlling positions, normally open switches cooperating with said control devices so as to be held closed when said devices are in their off positions, electrical connections between said control devices and said indicators so that both of said indicators are actuated when either control device is actuated from its off position and each control device being provided with means associated with said electrical connections to effect a graduated control of said indicators when said control device is moved to its controlling positions and said electrical connections including a connection through said switches so that when either control device is operated from its off position to effect a control of said indicators, its associated switch is opened to render the other control device inoperative to effect a graduated control of said indicators. 90 95 100 105 110

3. A signaling system comprising sending and receiving stations, electrical indicating devices in said stations, resistances in said stations, a contact control device in each of said stations, each of said contact devices being provided with an off-position and with a plurality of positions gradually changing the value of said resistance as the device is moved from off-position, electrical connections whereby each of said control devices actuates both of said indicators when either is moved from off-position, and means cooperating with each of said control devices when in off-position for closing a normally open circuit for the other control device. 115 120 125

4. A signaling system comprising sending and receiving stations, electrical indicating

devices in said stations, control devices in said stations for said indicators, each of said control devices being provided with an off position, and normally open switches maintained closed by said control devices respectively when in said off positions, the switch operated by one control device being in the circuit of the other control device so that when either control device is moved from its off position to operate the indicators the control circuit for the other control device is interrupted.

5 5. A signaling system comprising sending and receiving stations, electrical indicating devices in said stations, control devices in said stations for said indicators, each of said control devices being provided with an off position, normally closed switches maintained open by said control devices respectively when in off position, an alarm in said sending station in circuit with the switch in said receiving station and an alarm in said receiving station in circuit with the switch in said sending station so that when the control 10 device in either station is moved from its off position the switch in that station is closed to cause the alarm in the other station only to give a signal.

15 6. A signaling system comprising sending and receiving stations, an indicator in each of said stations, a supply source, resistances in said sending and receiving stations, connections whereby each of said resistances is connected across said supply source, taps on 20 said resistances, contact arms cooperating with said taps, normally open switches cooperating with said contact arms so as to be held closed by said contact arms when in off position, connections between one terminal 25 of each of said indicators and one side of said supply source, connections between the other terminals of said indicators and connections between the other terminals of said indicators and said contact arms, said latter connections 30 including a connection through the switch in said sending station to the contact arm in said receiving station and a connection through the switch in said receiving station to the contact arm in said sending station.

35 50 In witness whereof, I have hereunto set my hand this eighteenth day of February, 1927.

ALFRED C. FINNEY.
